RECLOSING SYSTEM FOR CIRCUIT BREAKERS, INCLUDING VARIABLE STROKE DISCONNECT SWITCH MEANS

Gustav E. Jansson, North Quincy, and Erwin Salzer, Brookline, Mass., assignors to Allis-Chalmers Manufacturing Company, Milwaukee, Wis.

Application September 8, 1951, Serial No. 245,724

10 Claims. (Cl. 317—22)

1
This invention relates to automatic reclosing systems for electric circuit interrupters and more particularly to means for controlling fluid blast circuit breakers having serially connected arcing and disconnect contacts for automatic high speed reclosing duty.

Heretofore, circuit breakers have been provided which remove a fault from a line and reclose within about ten to twenty cycles of a sixty cycle current wave. If the fault was not removed upon initial opening, the breaker would open a second time and would then remain permanently in the open position.

In fluid blast circuit breakers of standard design the weight and the stroke of the arcing or interrupting contacts are relatively small and the weight and stroke of the disconnect contacts are relatively large. Consequently, the speed of operation of the interrupting contacts is relatively rapid and that of the disconnect contacts relatively slow. Therefore, it is possible to fully separate the interrupting contacts in the order of 2.5 to 3.5 cycles of the current wave, while it takes about fifteen cycles of the current wave to achieve full separation of the disconnect contacts. In the case of rapid reclosing the reclosing time must be in the order of ten to twenty cycles, thus the movable disconnect contact of a fluid blast circuit breaker of conventional design is incapable of achieving the required speed of operation.

Rapid reclosing of a circuit breaker may be achieved by interlocking the arcing or interrupting contacts and the disconnect contacts so as to preclude opening of the latter upon initial opening of the former, but permitting opening of the latter upon repeated opening of the former.

A circuit breaker which is provided with such an interlock recloses the circuit upon initial opening thereof by means of the arcing or interrupting contacts rather than the disconnect contacts. Reclosing of the circuit by means of the interrupting contacts is a serious drawback since it imposes an additional heavy duty upon the interrupting contacts, for which they are generally not suited.

Therefore, in the invention claimed new and improved controlling means are provided for a circuit interrupting device which employs a plurality of cooperating arcing contacts in series with a plurality of cooperating disconnect contacts. Upon initial opening of the power circuit the arcing contacts separate followed by the separation of the disconnect contacts a predetermined distance. The arc is extinguished by a

2
blast of fluid under pressure and upon arc extinction the arcing contacts reengage followed by the reengagement of the disconnect contacts. If the circuit difficulty still exists the arcing contacts again separate followed by the separation of the disconnect contacts a second predetermined distance. The disconnect contacts separate the second time a greater distance than the first time to provide upon permanent interruption a sufficient amount of circuit insulation to keep the arc from restriking across the gap in the power circuit.

It is, therefore, one object of the present invention to provide a new and improved control system for a fluid blast circuit breaker having serially connected arcing and disconnect contact means to provide high speed reclosing service in which the electric circuit is interrupted by one pair of contacts and closed by another pair of contacts.

Another object of this invention is to provide a new and improved control system for high speed reclosing duty of a circuit interrupting device in which one pair of contacts interpose upon initial interruption a certain amount of circuit insulation and upon repeated interruption a larger amount of circuit insulation.

A further object of this invention is to provide a new and improved control system for a circuit breaker in which the electric circuit is interrupted by one pair of contacts in a medium of substantially higher dielectric strength than air at atmospheric pressure and is closed by a second pair of contacts arranged at atmospheric pressure.

A still further object of this invention is to provide a new and improved circuit breaker structure in which contact means are serially connected into a circuit with a pair of cooperating arcing contacts and are adapted to insert selectively into the electric circuit a relatively small amount of circuit insulation at a gap of relatively small length in a medium of relatively high dielectric strength and a relatively large amount of circuit insulation at a gap of increased length formed at least in part of air at atmospheric pressure.

Objects and advantages other than those set forth will be apparent from the following description when read in connection with the accompanying drawings, in which:

Fig. 1 is a diagrammatic view partly in elevation of a circuit breaker and operating system therefor embodying the present invention, the circuit breaker being open;

Fig. 2 is an enlarged view of the blast valve and arcing contact operating mechanism of Fig. 1 showing the contacts closed;

Fig. 3 is a view in cross section taken along the line III—III of Fig. 2 looking in the direction of the arrows;

Fig. 4 is a view of the latching mechanism shown in Fig. 1 but showing the mechanism in the disconnect contact closed position;

Fig. 5 is a diagrammatic view partly in elevation of a circuit breaker and operating system therefore employing another embodiment of the invention, the circuit breaker being open; and

Figs. 6 to 8, inclusive, show in front elevation three different positions of the linkage by which the disconnect contact of the circuit breaker illustrated in Fig. 5 is operated and restrained in closed position.

Referring to Fig. 1 of the drawing, the circuit breaker operating system comprises a supporting frame structure (not shown) topped by a platform 12. A storage tank 13 for air under pressure is arranged below platform 12. Platform 12 supports four insulating columns one of which, column 14, houses a disconnect switch comprising a stationary tulip contact 15 and a cooperating movable bayonet contact 16. An insulating column 17 houses a current transformer and another insulating column 18 is adapted to be rotated by a fluid motor 19 to cause opening and closing of a pair of cooperating arcing contacts 20 and 21. The contacts 20, 21, which are shown open in Fig. 1, are housed in a fourth insulating column which is generally designated 22. Column 22 comprises a lower insulator 23 in which an insulating blast tube 24 is arranged. A metallic blast tube 25 connects tank 13 with insulating blast tube 24. A casting 26 is supported on one end thereof by the hollow insulators 23 and 24. Attached to the other end of casting 26 is a disconnect and reclosing switch structure generally designated 30. The disconnect and reclosing switch structure is supported on the left side thereof by column 17. Casting 26 houses a differential type blast valve 31 under control of an auxiliary valve 32 and an operating linkage 33 for contact 21. Casting 26 supports in turn the hollow insulator 34 in which the tubular contact 20 is arranged. Insulator 34 is topped by a hood 35 defining two venting passages 36 for the exhaust of arc products. Stacks of parallel spaced plates 37 serve to cool the arc products before they are released to atmosphere. An electric line terminal 38 forms an integral part of hood 35.

Insulating column 14 is likewise topped by a hood 39 of which electric line terminal 40 forms an integral part. Column 14 consists of two tubular insulators 43 and 44 between which a casting 45 is arranged. Casting 45 defines an internal cylindrical surface 46 for a piston 47 supporting contact 16. Piston 47 is adapted to be operated by an insulating rod 48 which, in turn, is adapted to be operated by a metal rod 49.

Casting 45 of column 14 is conductively connected to the current transformer 50 within column 17 by a bridging member 51. A member 53 connects the current transformer within column 17 with the disconnect and reclosing switch 30.

The current path through the entire breaker structure is as follows: terminal 38, hood 35, stationary contact 20, movable contact 21, casting 26, disconnect and reclosing switch 30, member 53, current transformer 50 within column 17, bridging member 51, casting 45, bayonet contact 16, tulip contact 15, hood 39, terminal 40.

Referring more particularly to Figs. 2 and 3 in which the arcing contact mechanism is shown in contact closing position, casting 26 forms a housing for a blast valve generally designated 31.

Blast valve 31 comprises movable valve element 55 which is acted upon by helical biasing spring 56 tending to press valve element 55 against valve seat 57. Normally, air under pressure acts upon both the right and left end surfaces of valve element 55. In the closed position of valve 31 the effective area of the right fluid pressure reactive surface of valve element 55 is larger than the effective area of the left pressure reactive surface thereof. The air pressure tending to move valve element 55 from its normal position shown in Fig. 1 to the right is much less than the sum of the air pressure and the pressure of spring 56 both tending to press valve element 55 to the left against valve seat 57. The space situated at the right side of valve element 55 is adapted to be vented by means of pipe 58, auxiliary valve chamber 59 and an orifice 60 controlled by valve element 61.

Valve element 61 is adapted to be operated by means of stem 62 resting in slide bearings 63. Stem 62, in turn, is adapted to be operated by a crank mechanism which has generally been indicated at 70. Crank mechanism 70 is associated with an operating shaft 64 adapted to be operated by insulating column 18. The right end of stem 62 is surrounded by a helical biasing spring 65 of which one end rests on a collar 66 on stem 62, while the opposite end rests against valve housing 59.

Upon rotation of shaft 64 in the clockwise direction (as seen in Fig. 3) stem 62 moves to the right against the action of biasing spring 65 and moves valve element 61 from the left valve seat 68 to the right valve seat 69 of valve housing 59. Consequently, pipe 72 interconnecting a blast passage 73 with valve housing 59 is blocked and valve housing 59 vented to atmosphere. This causes the pressure on valve element 55 directed from left to right to exceed that directed from right to left, resulting in rapid opening of blast valve 31. The blast of air under pressure which is admitted from blast passage 73 to the gap formed between separated contacts 20, 21 tends to extinguish the arc which is initiated upon parting of movable contact 21 from stationary contact 20.

Separation of contacts 20 and 21 is effected by an arm 74 of crank mechanism 70. Arm 74 extends into a U-shaped abutment member 75 forming an integral part of rod 114 for actuating a contact operating toggle mechanism generally designated 33. That toggle mechanism comprises link 76 adapted to operate links 77 and 78, of which the former is adapted to operate two links 79 and 80. Links 77 and 78 are joined together at 81 and link 78 is fulcrumed at 82, in casting 26. Links 77 and 79 are joined together at 83, and link 79 is fulcrumed at 84, in casting 26. Links 78 and 80 are joined together at 85, and link 80 is pivotally connected at 86 to movable contact 21. Arm 74 and U-shaped abutment member 75 form a lost motion connection between shaft 64 and link 76 which is responsible for a small time delay between opening of blast valve 31 and separation of contacts 20 and 21.

When crank mechanism 70 is rotated in the clockwise direction (as seen in Fig. 3), arm 74 moves a predetermined distance before acting upon rod 114; then it engages the left abutment surface of member 75 moving rod 114 from right

to left. Rod 114 acts upon a piston 89 which, in turn, acts upon spring 90 in spring housing 91. Spring 90 provides the necessary contact pressure in the closed position of the breaker and is compressed by the action of arm 74 during the circuit interrupting operation. When link 76 is actuated by rod 114 to the left, toggle 77, 78 collapses. This causes rotation of link 79 about pivot 84 in the clockwise direction resulting in downward movement of the movable contact 21.

Movable contact 21 comprises a radially inner portion 92 and a radially outer portion 93. The outer portion 93 is telescopically arranged in a cylindrical guiding member 94. The inner portion 92 is, in turn, telescopically arranged in the outer portion 93. Spring 95 which is arranged between portions 92 and 93 biases the former upward. As clearly shown in Fig. 2, there is a certain axial play or lost motion between portions 92 and 93 and these two portions are provided with cooperating abutments 96 and 97, respectively, which limit relative movement of portions 92 and 93 when the latter is disengaged from tubular stationary contact 20.

Guiding member 94 is provided with spring biased contact segments 98 for reducing the contact resistance between that member and outer portion 93. In a similar way, outer portion 93 is provided with contact segments 99 for reducing the contact resistance between that portion and the inner portion 92. The inner portion 92 serves as arcing contact or interrupting contact while the outer portion 93 serves as current carrying contact. When the outer portion is actuated downward by toggle mechanism 32, the outer portion 93 separates first from stationary nozzle contact 20. Upon a predetermined downward travel of portion 93 abutment 97 thereof engages the flange or abutment 96 of portion 92, thus compelling the latter to separate from nozzle contact 20.

In order to cause reclosing of the blast valve 31 at the end of the circuit interrupting operation, an intermediate link 100 is arranged between arm 74 and connecting rod 81 of crank mechanism 70, and rod 87 is provided with an abutment member 88 adapted to be engaged by a stationary abutment 88a. Abutments 88 and 88a cause buckling of the toggle formed by members 87, 100 at the end of the circuit opening operation. This in turn permits spring 65 to move stem 62 to the left, thus moving valve element 61 from right valve seat 69 to left valve seat 68. Consequently, compressed air is being admitted to blast valve 31 through passage 72 and 58, resulting in closing of blast valve 31, thus precluding continued consumption of compressed air upon interruption of the circuit and interposition of a sufficient amount of circuit insulation by the disconnect and reclosing switch 30.

The disconnect and reclosing switch generally indicated at 30 comprises a stationary tulip type contact 101 made up of a plurality of spring biased contact fingers and a cooperating movable rod contact 102.

The pair of contacts 101 and 102 is arranged in a chamber 103 defined by an insulator 104. The left end of insulator 104 is supported by member 53 resting on the current transformer column 17 while its right end is supported by a cylinder 105 of a pneumatic motor comprising a piston 106. The piston 106 arranged in cylinder 105 operates contact 102 and is biased to contact closed position by a helical spring 107. Admission of air under pressure from casting 26 to cylinder 105 may

occur through duct 108, a check valve 120, port 109 and ports 110 and 123 in the left head of cylinder 105.

The flow of compressed air through duct 108 and ports 109, 110 is controlled by auxiliary piston valve 111 operated by a lever 112. Lever 112 cooperates with an abutment 113 secured to the operating rod 114 of the operating linkage 33 of interrupting contact 21. Piston valve 111 is provided with a venting port 115 and a spring 116 normally biasing valve 111 to the left, to open or venting position. Valve 111 begins to close upon engagement of lever 112 by abutment 113 and rotation of the former in the clockwise direction, as seen in Fig. 1. Cylinder 105 is provided with two lateral openings 117 and 118 of which one is arranged relatively close to contact 101 and the other relatively remote from contact 101.

On occurrence of a fault motor 19 rotates column 18, resulting in separating interrupting contact 21 from interrupting contact 20, opening of the blast valve 31 to produce an arc extinguishing blast across the gap formed between the separated contacts 20, 21 and closing of the auxiliary valve comprising a piston 111. Upon opening of blast valve 31 casting 26 is filled with air under pressure. Air under pressure is allowed to flow from casting 26 through duct 108 and ports 109, 110 into chamber 103, thus filling chamber 103 with a medium having a relatively high dielectric strength. Closing of valve 111 by abutment 113 and lever 112 occurs substantially simultaneously with the separation of the interrupting contacts 20, 21. Pressure rapidly built up in chamber 103 and cylinder 105 results in separation of contacts 101 and 102 by spring pneumatic motor 105, 106.

The operating and control arrangement for contacts 15 and 16 is as follows:

The operating mechanism for contact 16 comprises a spring biased pneumatic motor generally designated 125. Motor 125 and the motor comprising cylinder 105, piston 106 and spring 107 constitute an operator for the disconnect contact means 101, 102 and 15, 16. Motor 125 effects separation of contacts 15, 16 by spring means 126, and reclosing of contacts 15, 16 by pneumatic action. The helical spring 126 is arranged between a piston 127 and a cylinder 128 of motor 125. A piston type dump valve 129 which opens to atmosphere is provided to dump motor 125 when piston 127 approaches the top end of its stroke and also while it is impelled downward by the action of spring 126.

The operating linkage for contact 16 comprises two levers 130 and 131. The former is pivoted at 132 and the latter at 133. A tie link 134 interconnects levers 130 and 131. An operating rod 135 and a link 144 interconnect piston 127 of motor 125 and lever 131. Lever 131 carries a pin 136 which is provided with a roller 137 adapted to be engaged by cam surface 138 of a latch 139. Latch 139 is biased by a spring 140. Latch 139 is pivoted at 141 and controlled by a spring biased auxiliary latch 142. Auxiliary latch 142 is in turn controlled by tripping solenoid 143.

The pneumatic control system of the breaker includes pipeline 146 leading from the tank 13 to magnet valves 147 and 148. Both these valves are of the solenoid type; the former is a tripping valve energized when the breaker is to open; the latter is a closing valve energized when the breaker is to close. Pipeline 149 leads from tripping valve 147 to one end of pneumatic motor 19 and to one end of a piston valve 150. A pipeline 151 leads from closing valve 148 to the other

end of pneumatic motor 19 and to the other end of piston valve 150. Pipeline 159 connects one tap of the fluid motor piston valve unit 19, 150 with fluid motor 125. This pipeline is under the control of spring biased solenoid operated valve 152. The dump valve 129 of fluid motor 125 is operated by a lost motion mechanism and a rod 153 attached to lever 131.

The control circuit for the disconnect contact includes an auxiliary switch 154 adapted to be directly operated by the piston 155 of fluid motor 19.

The manual reclosing cutout switch 156 comprising a pair of switch arms insulated from each other is placed in the lower position shown to prepare the energizing circuit of tripping solenoid 143 when an automatic reclosing cycle is not desired.

Relay 157 is a conventional fault responsive time delay relay for initiating the operation of the breaker at the occurrence of a fault along the line for the protection of which the breaker is provided. Relay 158 is a conventional reclosing relay and is used for energizing closing solenoid valve 148 upon an initial separation of interrupting contacts 20 and 21 and for energizing tripping solenoid 143 upon repeated separation of interrupting contacts 20 and 21. Pushbutton switch 161 enables manual tripping and pushbutton switch 162 manual closing of the breaker; both reopen with a time delay.

The system being in the condition shown in Fig. 1, the open circuit breaker is closed manually by closing switch 162. This results in sequential closing of interrupting contacts 20, 21 and disconnect contacts 15, 16. More particularly, the operation of switch 162 causes energization of solenoid valve 148 from a battery 163 through switches 162 and 154. Valve 148 admits compressed air through pipe 151 to the left ends of motor 19 and of valve 150. Valve 150 moves to the right, thereby closing the left dumping port of motor 19, opening the right dumping port of motor 19, and opening pipe 159. Piston 155 also moves to the right to cause column 18 to rotate counterclockwise (as seen in Fig. 3) to close contacts 20, 21. Upon movement to the left by spring 146, valve 111 opens to vent cylinder 105 and contacts 101, 102 reclose if they were still open. Link 100 and connecting rod 87 are reset in the position shown while blast valve 31 remains closed. Switch 156 opens the energized circuit of valve 148, and the valve recloses.

When piston 155 reaches a predetermined position air may pass from the cylinder of motor 18 through pipe 159 and valve 152 to motor 125, causing upward movement of piston 127 against the bias of spring 126 and closing of contacts 15, 16. When piston 127 approaches the top end of its stroke, rod 153 moves valve 129 to dump the air contained in cylinder 128. The actuating means of contact 16 completes its stroke by momentum, roller 131 rolling on cam surface 133 during such movement. When contacts 15, 16 are closed, roller 136 reaches the notch in surface 138. Spring 140 causes latch 139 to pivot to cause engagement of the roller with the notch. Latch 142 is pulled into latching position to maintain latch 139 in the position reached thereby, in which it maintains contacts 15, 16 closed. The above referred to sequence of closing of contacts 20, 21 and 15, 16 is due to the interlocking of motors 19 and 125 through pipe 159 and to the time required to build up sufficient pressure be-

low piston 127 to move it against the bias of spring 126.

Manual opening of the circuit breaker is effected by actuating opening switch 161, causing energization of trip solenoid valve 147 from battery 163 through switches 161 and 154. Valve 147 admits air, through pipe 149, to the right ends of motor 19 and of valve 150. Valve 150 moves to the left, thereby opening the left dumping port of motor 19, closing the right dumping port of motor 19 and closing pipe 159.

Piston 155 also moves to the left to cause column 18 to rotate clockwise (as seen in Fig. 3). Blast valve 31 is thereby opened and contacts 20, 21 are separated to open the circuit. After the blast between contacts 20, 21 has had time to extinguish the arc, valve 111 admits air to cylinder 105 to cause opening of contacts 101, 102. Switch 154 opens the energizing circuit of valve 147, and the valve recloses.

Switch 154 also completes a circuit from battery 163 through switch 161, switch 156, solenoid 143 and switch 154, back to the battery. Solenoid 143 withdraws latch 142. The latter releases latch 139. Under the action of gravity and of spring 125, the disconnect contact actuating means moves latch 139 back to the unlatched position shown, roller 131 rolling on cam surface 133 while disconnect contact 16 returns to the open position shown.

When piston 155 approaches the end of its stroke, abutment 86a causes collapse of the toggle formed by link 100 and connecting rod 87 to reclose blast valve 31. In order to preclude a reclosing operation when it is desired to manually effect a permanent interruption of the circuit, switches 156 and 162 may be provided with an interlock 164 so that switch 162 cannot be operated as long as switch 156 is in the upper or reclosing position.

The circuit breaker being closed, relay 157 is energized upon occurrence of a fault condition. If switch 156 is in the lower position shown, relay 157 merely causes tripping of the circuit breaker 45 as if switch 161 had been closed as above described.

If switch 156 is placed in the upper (reclosing) position, relay 157 likewise connects the solenoid of valve 147 to the battery. In addition, the motor of reclosing relay 158 is connected to the battery through relay 157 and switch 156. Reclosing relay 158 starts and closes a circuit maintaining its motor energized while its drum completes a full revolution. Energization of the circuit of solenoid valve 147 causes admission of compressed air to the right side of fluid motor 19 and piston valve 150. Consequently, piston 155 of motor 19 and the movable valve element of valve 150 are moved from right to left. This movement of piston 155 causes a rotation of column 18 which in turn causes opening of blast valve 31 and separation of contacts 20 and 21. Upon separation of contacts 20 and 21, contacts 101 and 102 are separated by the action of fluid motor 105, 106, as previously described. Toggle 87, 100 collapses and recloses blast valve 31. However, check valve 120 retains the air in cylinder 105 and thus prevents premature reclosure of contact 102. Relay 157 returns to the position shown.

The movement of piston 155 to the left also operates the auxiliary switch 154, which deenergizes solenoid valve 147 and closes the circuit of solenoid valve 148 through switch 153. Consequently the flow of compressed air through pipe

149 is interrupted and a flow of compressed air is established through pipe 151. The latter flow causes a motion of the piston 155 of motor 19 and of the movable element of valve 150 from left to right. This movement of piston 155 results in a rotation of insulating column 18 whereby interrupting contacts 20 and 21 are reclosed. The auxiliary valve 111 for controlling the operation of contacts 101, 102 is opened by the biasing spring 116 substantially simultaneously with re-closure of interrupting contacts 20, 21 as abutment 113 is moved to the right by column 18. This results in venting of fluid motor 105, 106 through vent opening 115 and closing of contacts 101, 102 after contacts 20, 21 have reclosed.

The movement of the valve element of piston valve 150 to the right causes admission of air under pressure from the cylinder of fluid motor 19 to pipe 159. Pipe 159, however, is sealed by solenoid valve 152 since, as piston 155 moves from left to right, auxiliary switch 154 energizes solenoid valve 152 from battery 163 through relay 158. Solenoid valve 152 closes against the action of its biasing spring. Switch 154 also deenergizes solenoid valve 148, which returns to the closed position shown.

What happens further depends on whether or not the fault still prevails at the time when contacts 101 and 102 reengage. Relay 158 returns to the position shown but if the fault does not prevail during that time, nothing else happens, i. e., service continuity is maintained. If the fault still persists at the time when contacts 101 and 102 reengage, the operating cycle of the breaker continues and a permanent interruption of the circuit is effected by the breaker.

Permanent interruption is initiated by reenergization of relay 157, resulting in reopening of solenoid valve 147 and readmission of compressed air to motor 19. Piston 155 of motor 19 then moves from right to left, which results in momentary opening of blast valve 31 and separation of interrupting contacts 20 and 21, and, therefore, re-interruption of the faulted circuit. Relay 157 again returns to the position shown. Thereafter contacts 101 and 102 part under the action of fluid motor 105, 106. At that time the reclosing relay 158 energizes the tripping relay 143 through switch 154, whereby latch 142 is moved in counterclockwise direction, thus releasing main latch 139. Roller 131 is deprived of its support and spring 126 is free to move linkage 130, 134, 131 from its upper position, shown in Fig. 4, to its lower position, shown in Fig. 1. This completes the opening operation of the circuit breaker and results in the formation of a gap of required length between contacts 15 and 16.

Upon permanent interruption contacts 20, 21 and 15, 16 remain separated. Contacts 101 and 102 reclose when contacts 15, 16 are separated a safe distance from each other. The time at which contacts 101 and 102 reclose is determined by the size of a bleed hole 121 by which chamber 103 is vented. To be able to vary that time, bleed hole 121 may be provided with an adjustable needle valve 122.

It will be obvious from the foregoing that this embodiment of the invention shown comprises three principal pairs of contacts, i. e., a pair of arcing or circuit interrupting contacts 20, 21, a separate pair of circuit closing contacts 101, 102 and a separate pair of disconnect contacts 15, 16.

It will also be apparent from the foregoing that each pair of contacts has a separate operator. 75

The pair of arcing or interrupting contacts 20, 21 is separated and closed by the fluid operator 19, the pair of closing contacts 101, 102 is separated and closed by the combined fluid and spring 5 motor 30 and the disconnect contacts 15, 16 are separated and closed by the combined fluid and spring motor 125.

Fluid motor 19 and combined fluid and spring motor 125 are arranged at ground potential, 10 whereas combined fluid and spring motor 30 is arranged at the same elevated potential as housing 26 and all the metallic parts that are associated with it, including the blast valve 31.

Fig. 5 illustrates another embodiment of the 15 invention as applied to an air blast circuit breaker structure of the same type as illustrated in Fig. 1. The circuit breaker structures of Figs. 1 and 5 are identical except that the disconnect and reclosing switch 30 and its operating mechanism 20 have been omitted from the embodiment of Fig. 5 and the operating means for the disconnect switch 15, 16 has been modified so that the disconnect contacts 15, 16 may be opened to provide a plurality of air gaps of varying size. Structural 25 elements of Fig. 5 which are identical with those of Fig. 1 have the same reference characters.

On the occurrence of a fault on the power circuit controlled, motor 19 rotates column 18, resulting in the separation of arcing contacts 20 and 21 and the opening of the blast valve 31 to produce an arc extinguishing blast across the gap formed between the separated contacts 20, 21. Disconnect contacts 15 and 16 separate instantly after the extinction of the arc formed between arcing contacts 20, 21. Contacts 20, 21 are caused to reengage by the action of motor 19 and rotating column 18. The lowest position of contact 16 during the initial arc extinguishing operation is illustrated in Fig. 5 by dotted lines. 30 If the fault condition still prevails at the time contacts 15 and 16 reengage, the circuit breaker is tripped again, resulting in sequential separation of contacts 20, 21 and 15, 16. This time, however, disconnect contact 16 is actuated to 35 the position shown in full lines in Fig. 5.

The operating and control means for achieving 40 this particular type of operation is as follows:

The operator or operating mechanism for contact 16 comprises two spring biased pneumatic 45 motors 170 and 125. Motor 170 effects the short opening stroke of contact 16 and recloses contacts 15 and 16. Motor 125 effects the long opening stroke of contact 16 and recloses contacts 15 and 16 after contact 16 has reached its 50 lowermost position shown in Fig. 5. Motor 170 effects separation of contacts 15, 16 by spring means 171 and effects reclosing of contacts 15, 16 by pneumatic action. Spring means 171 are arranged between piston 172 and cylinder 173.

The operating linkage for contact 16 comprises two levers 174 and 175. The former is pivoted at 176 and the latter at 177. Tie link 178 interconnects levers 174 and 175. Operating rod 179 interconnects piston rod 180 of motor 125 and lever 175. Lever 175 is provided with a roller 180 adapted to be engaged by the main latch 139 under the action of biasing spring 140. Main latch 139 is pivoted at 141 and controlled by the spring biased auxiliary latch 142. Auxiliary latch 142 is in turn controlled by tripping solenoid 143.

The piston rod 181 of fluid motor 170 is connected to lever 174 by a link 182. A roller 176 on the pin interconnecting link 182 and lever 174 is guided by cam surface 183 and held in posi-

tion by spring biased latch 184. Latch 184 is in turn controlled by a latch 185 adapted to be operated by a tripping solenoid 186. Pipeline 188 connects one tap of the fluid motor piston valve unit 19, 150 with fluid motor 170. This pipeline is under the control of solenoid operated valve 187. Pipeline 159 connects another tap of the fluid motor piston valve unit 19, 150 with fluid motor 125. This pipeline is under the control of latch checking valve 189 which insures that the main closing motor 125 cannot be supplied with fluid under pressure unless the latch mechanism 184, 185 is in locked position.

The energizing circuit of solenoid operated valve 187 includes an interlock switch 190 adapted to be operated by piston rod 181 of fluid motor 170 by means of an operating rod 191. Switch 190 is spring biased to open position in which it prevents the solenoid of solenoid operated valve 187 from being energized. When the piston 172 of fluid motor 170 moves to its upper position, piston rod 181 acts upon operating rod 191 to close interlock switch 190.

The circuit breaker illustrated open in Fig. 5 is manually closed by means of pushbutton 162. This results in operation of valve 149 to permit fluid under pressure from tank 13 to actuate piston 155 of motor 19 and valve 150 from left to right. After piston 155 has completed part of its stroke air flows from the cylinder of motor 19 through valve 150 and pipeline 159 to motor 125. Piston 127 is actuated upward against the bias of spring 126 to close the disconnect contacts 15 and 16 through the levers 174, 175 and 178 and is latched in place by latches 139 and 142. Dump valve 129 remains closed during most of the closing stroke of the breaker as a result of the lost motion connection associated with rod 153 and the dump valve actuating rod. At the end of the stroke of piston 155 from left to right, switch 154 interrupts the energizing circuit of valve 148.

Manual opening of the circuit breaker illustrated in Fig. 5 may be effected by actuating pushbutton 161, causing energization of tripping valve 151 and the same sequence of operation as described above for the embodiment illustrated in Fig. 1. During manual opening, switch 156 is moved to its lower position to preclude automatic reclosing of the breaker.

If reclosing cutout switch 156 is in the upper position an automatic reclosing sequence of operation of the circuit breaker system will occur. The circuit breaker being closed, energization of relay 157 starts reclosing relay 158, which locks itself in circuit. Energization of relay 157 also results in closing of the circuit of solenoid valve 147 through switch 154 and consequently in admission of compressed air to the right side of fluid motor 19 and piston valve 150. Piston 155 of motor 19 and the movable valve element of valve 150 are thereby moved from right to left. This movement of piston 155 causes a rotation of column 18 which in turn causes momentary opening of blast valve 31 and in separation of contacts 20 and 21. The movement of piston 155 to the left operates auxiliary switch 154.

When piston 155 of motor 19 reaches its left position, switch 154 energizes the circuit of solenoid 186 through reclosing relay 158. Solenoid 186 unlatches latch 184 and spring 171 of motor 170 expands, thereby causing lever 174 to rotate counterclockwise about the point where it is hingedly connected to link 178. Roller 176 moves up along the cam surface 183 as disconnect con-

5

tact 16 is moved a reduced stroke to the position shown in dotted lines in Fig. 5. The position of the latch members 184, 185, 142 and 139 for the reduced stroke of the disconnect contact 16 is illustrated in Fig. 8. At that time piston rod 181 closes valve 189 and switch 190. Relay 157 returns to the position shown.

Switch 154 in its movement from right to left also deenergizes solenoid 186 so that latch 185 may reset. However, while piston 172 moves downward roller 176 moves along an extension of latch 184 so that latches 184 and 185 are prevented from returning to the latching portion of Figs. 5 and 7 until piston 172 has completed its downward stroke.

When piston 155 of motor 19 is in its left position, switch 154 causes opening of the solenoid valve 147 and closing of the circuit of the solenoid valve 148 through relay 158. Consequently,

20 the flow of compressed air through pipe 149 is interrupted and a flow of compressed air is established through pipe 151. The latter flow causes a motion of the piston 155 and of the movable element of valve 150 from left to right.

25 This movement of piston 155 results in a rotation of insulating column 18 which, in turn, recloses contacts 20 and 21.

Movement of the valve element of piston valve 150 to the right causes admission of air under 30 pressure from the cylinder of fluid motor 19 to the pipes 159 and 128. Compressed air admitted to pipe 159 remains ineffective since that pipe is blocked by latch checking valve 189 moved to closed position through the previous 35 operation of spring 171 and rod 181.

As piston 155 of motor 19 moves from left to right auxiliary switch 154 is moved from right to left and closes the circuit which energizes solenoid valve 187 through switches 159 and 156 and 40 relay 158. Valve 187 is thereby opened and compressed air is then admitted to the cylinder 173 of fluid motor 170, causing the downward movement of piston 172 against the action of spring 171, thus reclosing contacts 15 and 16. Reclosing 45 of contacts 15 and 16 results in reclosing of the controlled power circuit.

What happens further depends on whether or not the fault still prevails at the time disconnect contacts 15 and 16 reengage. If the fault does 50 not prevail at that time the continuity of the system is maintained. If the fault still persists, the circuit breaker proceeds to effect a permanent interruption of the power circuit.

Upon reclosure of contacts 15, 16, permanent 55 interruption is initiated by reenergizing relays 151 and 147, resulting in admission of compressed air to motor 19. Piston 155 of motor 19 then moves from right to left, resulting in momentary opening blast valve 31 and in separation of arc- 60 ing contacts 20, 21. The power circuit is again interrupted.

During the initial interrupting sequence, motor controlled relay 158 moved so that at this 65 time the control circuit passing therethrough and through switch 154 will energize solenoid 143 but not solenoid 186.

Solenoid 143 causes auxiliary latch 142 to move counterclockwise and release main latch 70 139. Roll 130, as shown, in Fig. 7 is deprived of its support and spring 126 is free to move linkage 174, 175, 178 from its position shown in Fig. 7 to its position shown in Figs. 5 and 6. This completes the opening operation of the circuit breaker and results in separating the disconnect

75

contacts their full stroke as distinguished from part stroke separation.

Although but two embodiments of the present invention have been illustrated and described, it will be apparent to those skilled in the art that various changes and modifications may be made therein without departing from the spirit of the invention or from the scope of the appended claims. In particular, while the specific structures shown in the drawing are high voltage air blast circuit breakers of the axial type, the invention is also applicable to circuit breakers of other types such as for instance oil poor or small volume oil circuit breakers.

Features disclosed but not claimed herein are claimed in U. S. Patent No. 2,568,008, granted upon the application of Gustav E. Jansson.

It is claimed and desired to secure by Letters Patent:

1. In combination, an electric circuit, a circuit breaker comprising serially connected cooperating arcing contact means and disconnect contact means, said disconnect contact means arranged to insert circuit insulation into said circuit selectively at relatively small gap length and at relatively large gap length, means responsive to an overload condition of said circuit for causing separation of said arcing contacts and interruption of said circuit at the gap formed between said arcing contacts, means operative upon initial interruption of said circuit at said arcing contacts for causing said disconnect contact means to open and to insert circuit insulation at said small gap length into said circuit, means operative upon said insertion of circuit insulation at said small gap length for causing said arcing contacts and said disconnect contact means to be reclosed sequentially, and means operative only upon repeated interruption of said circuit at said arcing contacts for causing said disconnect contact means to insert circuit insulation at said large gap length into said circuit.

2. In combination, an electric circuit, a circuit breaker comprising serially connected arcing contacts and disconnect contacts connected in said circuit, an arcing contact operator for providing relative short stroke movements between said arcing contacts, a disconnect contact operator for providing selectively relative short stroke and long stroke movements between said disconnect contacts, means responsive to an overload condition of said circuit for actuating said arcing contact operator to separate said arcing contacts, means for actuating said disconnect contact operator to separate said disconnect contacts at small gap length upon initial opening of said arcing contacts, means for actuating said arcing contact operator to reclose said arcing contacts upon separation of said disconnect contacts at small gap length, means for actuating said disconnect contact operator to reclose said disconnect contacts upon separation thereof at small gap length, and means operative only upon repeated interruption of said circuit at said arcing contacts for actuating said disconnect contact operator to separate said disconnect contacts at large gap length.

3. An electric circuit breaker comprising in combination, a source of gas under pressure, a pair of relatively movable cooperating arcing contacts, means for actuating said arcing contacts, means for establishing and maintaining a blast of gas from said source adjacent said arcing contacts when separated by said actuating means, a pair of relatively movable disconnect contacts connected in series with said arcing con-

tacts, a first disconnect contact operator provided to effect small relative movements between said disconnect contacts, a second disconnect contact operator provided to effect large relative movements between said disconnect contacts, tripping means for actuating said arcing contact operator to separate said arcing contacts, means for actuating said first disconnect contact operator to separate said disconnect contacts upon initial separation of said arcing contacts, means for actuating said arcing contact operator to close said arcing contacts upon separation of said disconnect contacts, means for causing said first disconnect contact operator to close said disconnect contacts upon reengagement of said arcing contacts, and means operative only upon repeated opening of said arcing contacts for actuating said second disconnect contact operator to separate said disconnect contacts.

4. In combination, an electric circuit, a circuit breaker comprising a pair of cooperating arcing contacts, contact means in series with said arcing contacts for selective insertion into said circuit a relatively small amount of circuit insulation at a gap of relatively small length formed in a medium of relatively high dielectric strength and of a relatively large amount of circuit insulation at a gap of increased length formed in air at atmospheric pressure, means responsive to an overload condition of said circuit for separating said arcing contacts to interrupt said circuit, means operative upon initial interruption of said circuit at said arcing contacts for causing said contact means to insert circuit insulation at small gap length into said circuit, means operative upon insertion of circuit insulation at small gap length for reengaging said arcing contacts, means for reclosing said additional contact means upon reclosing of said arcing contacts, and means operative only upon repeated interruption of said circuit at said arcing contacts for causing said additional contact means to insert circuit insulation at large gap length into said circuit.

5. In combination, an electric circuit, a circuit breaker comprising a pair of circuit interrupting contacts, a pair of circuit closing contacts, and a pair of disconnect contacts, all said contacts being serially connected in said circuit, an interrupting contact operator for effecting relative short stroke movements between said interrupting contacts, a closing contact operator for effecting relative short stroke movements between said closing contacts, fault responsive tripping means for causing said interrupting contact operator to open said interrupting contacts on the occurrence of a fault in said circuit, means for causing said closing contact operator to open said closing contacts upon initial opening of said interrupting contacts, means for causing said interrupting contact operator to reclose said interrupting contacts upon opening of said closing contacts, means for causing said closing contact operator to reclose said closing contacts upon reclosing of said interrupting contacts, a disconnect contact operator for effecting relative long stroke movements between said disconnect contacts, and means operative only upon repeated opening of said interrupting contacts for causing said disconnect contact operator to open said disconnect contacts.

6. In combination, an electric circuit, a circuit breaker comprising a pair of cooperating interrupting contacts of the nozzle and plug type, a pair of closing contacts of the engageable finger

type, and a pair of disconnect contacts of the engageable finger type, all said contacts being serially connected into said circuit, an interrupting contact operator for effecting relative short stroke movements between said interrupting contacts, a closing contact operator for effecting relative short stroke movements between said closing contacts, fault responsive tripping means for causing said interrupting contact operator to open said interrupting contacts to draw an arc therebetween, means for producing an arc extinguishing blast of fluid across the gap formed upon opening of said interrupting contacts, means for causing said closing contact operator to open said closing contacts upon opening of said interrupting contacts and extinction of said arc, means for causing said interrupting contact operator to reclose said interrupting contacts upon opening of said closing contacts, means for causing said closing contact operator to reclose said closing contacts upon reclosing of said interrupting contacts, a disconnect contact operator for effecting relative long stroke movements between said disconnect contacts, and means operative only upon repeated opening of said interrupting contacts for causing said disconnect contact operator to open said disconnect contacts.

7. In combination, an electric circuit, a circuit breaker comprising a pair of circuit interrupting contacts, a separate pair of circuit closing contacts, and a separate pair of disconnect contacts, said interrupting contacts, closing contacts and disconnect contacts being serially connected into said circuit, an operator for effecting relative movement between said interrupting contacts, an operator for effecting relative movement between said closing contacts, means responsive to an overload condition of said circuit for opening said interrupting contacts, means operative upon opening of said interrupting contacts for opening said closing contacts, means operative upon opening of said closing contacts for closing of said interrupting contacts, means operative upon closing of said interrupting contacts for reengaging said closing contacts, a source of gas under pressure, means for admitting a blast of gas from said source adjacent said interrupting contacts during separation thereof, means for admitting gas under pressure from said source adjacent said closing contacts during the separation thereof, an operator for effecting relative movement between said disconnect contacts, and means operative only upon repeated opening of said interrupting contacts for separating said disconnect contacts.

8. An electric circuit breaker comprising in combination, a source of gas under pressure, an insulating blast passage connected at one end thereof with said source, a main valve arranged adjacent the opposite end of said passage for controlling a blast of gas issuing therefrom, a pair of relatively movable circuit interrupting contacts arranged adjacent the region of said blast, an interrupting contact operator arranged at ground potential, a rotatable insulating column adapted at one end thereof to be rotated by said interrupting contact operator, and at the opposite end thereof arranged to operate one of said interrupting contacts and to initiate the operation of said main valve, a contact chamber, an auxiliary valve under the control of said insulating column for admitting gas under pressure from said passage to said chamber, a pair of relatively movable circuit closing contacts arranged in said chamber and arranged to be

connected in series with said interrupting contacts, closing contact operating means arranged at an elevated potential and under the control of said column for effecting relative movement between said closing contacts, tripping means responsive to a circuit condition for actuating said interrupting contact operator to separate said interrupting contacts, means for actuating said closing contact operating means to open said closing contacts upon opening of said interrupting contacts, means for actuating said interrupting contact operator to close said interrupting contacts upon opening of said closing contacts, means for actuating said closing contact operating means to reengage said closing contacts upon closing of said interrupting contacts, a separate pair of relatively movable disconnect contacts connected in series with said interrupting contacts and said closing contacts, a disconnect contact operator for effecting relative movement between said disconnect contacts, and means for causing said disconnect contact operator to separate said disconnect contacts upon repeated opening of said interrupting contacts.

9. An electric circuit breaker comprising in combination, a source of gas under pressure, means defining a first contact chamber, a pair of relatively movable circuit interrupting contacts in said first contact chamber, means defining a second contact chamber arranged generally transverse with respect to said first contact chamber, a pair of relatively movable circuit closing contacts in said second contact chamber arranged to be connected in series with said interrupting contacts, an operator for effecting relative movement between said closing contacts, fault responsive means for opening said interrupting contacts, means operative upon opening of said interrupting contacts for opening said closing contacts, means operative upon opening of said closing contacts for closing of said interrupting contacts, means operative upon closing of said interrupting contacts for reengaging said closing contacts, common means for admitting gas under pressure from said source to said first contact chamber and said second contact chamber, a pair of relatively movable disconnect contacts connected in series with said interrupting contacts and said closing contacts, an operator for effecting relative movement between said disconnect contacts, and means operative only upon repeated opening of said interrupting contacts for causing opening of said disconnect contacts.

10. An electric circuit breaker comprising in combination, a source of gas under pressure, a pair of relatively movable circuit interrupting contact comprising a nozzle shaped contact and a cooperating plug shaped contact, a pair of relatively movable circuit closing contacts comprising a plurality of finger type contact elements arranged to engage a cooperating contact element on opposite surfaces thereof, a first operator for actuating said pair of interrupting contacts, a second operator for actuating said pair of closing contacts, fault responsive means for causing admission of gas under pressure from said source adjacent said pair of interrupting contacts and adjacent said pair of closing contacts and for opening said pair of interrupting contacts, means for actuating said second operator to open said pair of closing contacts upon opening of said pair of interrupting contacts and extinction of the arc formed therebetween, means

17

for actuating said first operator to reclose said pair of interrupting contacts upon opening of said pair of closing contacts, means for actuating said second operator to reclose said pair of closing contacts upon reclosing of said pair of interrupting contacts, a pair of relatively movable disconnect contacts, means for serially connecting said pair of interrupting contacts, said pair of closing contacts and said pair of disconnect contacts into a circuit, a third operator for effecting relative movement between said pair of disconnect contacts, and means operative only upon

18

repeated opening of said pair of interrupting contacts for causing said third operator to open said pair of disconnect contacts.
